POTHEAD

Alwin G. Steinmayer, Milwaukee, Wis., assignor
to Line Material Company, South Milwaukee,
Wis., a Corporation of Delaware

Application February 12, 1930. Serial No. 427,803

8 Claims. (Cl. 173—353)

This invention relates particularly to pot heads or cable duct bells of the type illustrated in my copending application Serial No. 310,333, filed Oct. 4, 1928, of which this application is a continuation as to all common subject matter, and wherein a hermetic seal is provided for the end of a cable, and through which the conductor or conductors of the cable are brought outwardly to be connected with the conductor or conductors of an aerial system or the like, and has as an object the provision of novel and efficient means for facilitating the connection of the conductors.

Heretofore, it has been customary to solder or sweat a terminal member to the stripped end of the cable conductor and to extend the same outwardly through the pot head cover to be connected with its respective aerial conductor. This method has several objections, the foremost of which is the difficulty with which the terminal member is sweated or soldered to the end of the cable conductor, this being especially true where the cable conductor is heavy and stiff.

With the above objection in mind, the present invention contemplates as another object the provision of means connectible with the end of a cable without necessitating soldering.

Another object of this invention resides in the provision of clamping means engageable with the extended end of the cable conductor and having means for likewise clamping a lead-in or conductor wire thereto, to have a good electrical connection with the cable conductor.

A further object of this invention resides in the provision of a tapered split sleeve engageable with the end of a cable conductor, and means whereby the sleeve may be clamped to bind the end of the conductor.

And a still further object of this invention resides in removably mounting the clamping means whereby the insulated cable may be brought out through the pot head to facilitate its preparation for connection with the clamping means.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated a complete example of the physical embodiment of my invention constructed according to the best modes I have so far devised for the prac-

tical application of the principles thereof, and in which:

Figure 1 is a side view of a pot head for a single conductor cable illustrating the application of this invention, and having parts broken away and in section; and

Figure 2 is a perspective view of the clamping contact sleeve or bushing and its supporting washer removed from the pot head structure.

Referring now more particularly to the accompanying drawing, the numeral 5 represents the casing of a pot head or cable duct bell of any suitable design and which in the present instance is adapted particularly for a single conductor cable 6. The cable 6 is connected with the lower portion of the casing in any conventional manner, and its core or conductor 7 extends upwardly through an outlet bushing 8 preferably formed of porcelain or other suitable insulating material.

The upper open end of the bushing mounts an exteriorly threaded cap member 9 apertured, as at 10, to provide a continuation of the bore 11 in the bushing, and supported by the cap member 9 is a washer or disc member 12 which forms a support for a clamping bushing or sleeve 13 preferably formed of lead or other suitable deformable metal. The washer 12 has a central downwardly directed boss 14 which projects into the aperture 10 to align the washer with the cap member and its bore 15 is slightly larger than the diameter of the bared end of the conductor 7.

The diameter of the bore 16 of the clamping bushing or sleeve is of a diameter to snugly engage the bared end of the conductor 7 which projects upwardly through the opening in the washer and its external surface is conical in shape so that downward force applied onto the bushing by a clamp nut 17, whose lower end is threaded onto the cap member 9, wedges the bushing between its tapered bore 18 and the adjacent portion of the conductor to provide a perfect electrical engagement between the conductor and the clamp nut. As is best illustrated in Figure 2, alternate longitudinal slots 19 and 20 extended downwardly and upwardly, respectively, into the body of the bushing provide spaces to permit the contraction of the bushing during the clamping action.

To prevent relative movement between the bushing 13 and its supporting washer 12, diametrically opposed projections 21 extend downwardly from the under surface of the bushing to be received in grooves or recesses 22 formed

in the upper surface of the supporting plate in communication with its bore 15.

Removal of the bushing 13 and its supporting washer 12 permits the entire cable conductor 5 with its insulation to be brought out through the pot head to facilitate cutting the same to its proper length and otherwise performing the necessary operations preparatory to its connection with the clamp nut in the manner herein 10 described.

The upper end of the clamping nut 17 is reduced in diameter and exteriorly threaded, to provide a stud 23 upon which a lateral extension 24 may be clamped by a nut 25. The outer end 15 of the lateral extension has an upwardly directed exteriorly threaded boss 26 provided with a tapered bore 27 to receive a sleeve 28 of lead or other deformable metal. The sleeve 28 forms a bushing for the adjacent end of an aerial conductor 29 and as the outer cylindrical surface of the sleeve is tapered in both directions, tightening 20 of a nut 30 threaded on the projection 26 serves to tightly clamp the bushing onto the conductor and provide a good electrical connection 25 between it and the laterally extended member 24.

Although the foregoing description and the illustration shows the invention applied to a single conductor cable, it is understood that the 30 application is the same in instances where the cable is composed of a number of conductors.

From the foregoing description taken in connection with the accompanying drawing, it will be readily apparent to those skilled in the art to 35 which an invention of the character described appertains, that I provide novel means for connecting an aerial conductor with the conductor of a cable extending outwardly through a pot head, in which variations in the length of the 40 cable conductor are readily accommodated without in any way imposing strains on the cable, in which the connecting means forms a support for the cable, and in which the connection with the cable is readily facilitated by permitting the entire 45 diameter of the insulated cable conductor to extend from the pot head bushing.

What I claim as my invention is:

1. In a pot head having a tubular outlet member, a cable conductor having a portion within 50 the tubular outlet member and a terminal member, means for connecting the terminal member with the cable conductor comprising, a sleeve engageable with the cable conductor, readily removable means for supporting the sleeve in operative position from the tubular outlet member, means on said support cooperating with means on said sleeve to prevent relative rotation therebetween, means for connecting the terminal member with the tubular outlet member, and 55 means whereby the connection of the terminal member with the tubular outlet member cooperates with the removable means for supporting the sleeve to wedge the same between the terminal member and the conductor.

2. The combination with a pot head having a tubular outlet member, a cable conductor projectable through the tubular outlet member and a terminal member, of means for connecting the terminal member with the cable conductor comprising a sleeve engageable with a portion of the cable conductor from which the insulation has been stripped, a support for the sleeve, means on said support cooperating with means on said sleeve to prevent relative rotation therebetween, said support having an aperture slightly larger 65

than the diameter of the bared portion of the cable conductor and being removable to permit the extension of an insulated portion of the cable beyond the tubular outlet member, means for drawing the terminal member toward the tubular outlet member, and means whereby movement of the terminal member toward the tubular outlet member wedges the sleeve between the terminal member and the cable conductor.

3. In a device of the character described, an apertured outlet member, a cable conductor projectable through the outlet member to facilitate baring of its end, a terminal member, a sleeve engageable with the bared end of the cable conductor, means for supporting the sleeve from the tubular outlet member, means on said support cooperating with means on said sleeve to prevent relative rotation therebetween, said support means partially closing the aperture through the outlet member and being removable to permit the projection of the full diameter of the conductor beyond the outlet member, means for connecting the terminal member with the outlet member, and means whereby the sleeve is impinged between the terminal member and the cable conductor upon engagement of the terminal member with the outlet member.

4. In a device of the character described, an apertured outlet member, an insulated conductor projectable through the outlet member to facilitate baring of its end, a sleeve engageable over the bared portion of the conductor, a supporting member for the sleeve, means on said support cooperating with means on said sleeve to prevent relative rotation therebetween, said supporting member partially closing the aperture through the outlet member and being removable to permit the extension of the full diameter of the conductor through the outlet member, a clamping nut connectable with the outlet member, and means whereby the connection of the clamping nut with the outlet member wedges the sleeve between the clamping nut and the conductor to electrically connect the conductor with the clamping nut and to mechanically connect the conductor with the outlet member.

5. In combination with a pot head having a tubular bushing and a conductor projectable therethrough, a cap member on the bushing having an aperture sufficiently large to permit the full diameter of the conductor to be passed therethrough to facilitate preparing the same for connection with a terminal member, a yieldable sleeve engageable with a bared portion of the conductor, a supporting member mounted on the cap member and partially closing its aperture to form a support for the yieldable sleeve adjacent the conductor, means on said support cooperating with means on said sleeve to prevent relative rotation therebetween, a clamping nut engageable with the cap member, and means whereby engagement of the clamping nut with the cap member wedges the yieldable sleeve between the clamping nut and the conductor.

6. In combination with a pot head having a tubular bushing, a cable conductor extended through the bushing, a cap member carried by the bushing and having an aperture sufficiently large to receive the full diameter of the cable conductor to permit the same to be projected beyond the tubular bushing to facilitate baring its end, a yieldable sleeve engageable with the bared end of the cable conductor, a member supported by the cap member and forming a support for the yieldable sleeve adjacent the cable con-

ductor, means on said support cooperating with means on said sleeve to prevent relative rotation therebetween and terminal means cooperating with the last mentioned member to wedge the sleeve between it and the conductor whereby the conductor is anchored to the tubular member and convenient means are provided for electrically connecting a lead-in conductor with the said conductor.

10 7. In a device of the character described, a tubular member, a cap member carried by the tubular member and having an opening forming substantially a continuation of the bore in the tubular member, a conductor within the tubular member and projectable through the cap member opening to facilitate baring of its end portion, a sleeve engageable with the bared end portion of the conductor, a member partially closing the opening through the cap member and supporting the sleeve from the cap member, means on said support cooperating with means on said

sleeve to prevent relative rotation therebetween and terminal means cooperating with the last mentioned member to wedge the sleeve between it and the conductor whereby the conductor is anchored to the tubular member and convenient means are provided for electrically connecting a lead-in conductor with the said conductor.

15 8. In a device of the character described, a threaded cap having a port therethrough, a disc member detachably supported on the outer end of the cap and having a boss projecting into said port and having an opening therethrough to accommodate a cable, a clamping bushing supported from said disc member outwardly of the cap and having a tapered conical face, and a nut member having a threaded engagement with the cap and having a tapered conical recess, the walls of which engage said clamping bushing to compress the same between said nut member and said cable to form an electrical connection.
